(57) **CLAIM**

The ornamental design for a flashlight, as shown and described.

DESCRIPTION

FIG. 1 is a perspective view of a flashlight showing my new design;

FIG. 2 is a top plan view thereof;

FIG. 3 is a front elevational view thereof;

FIG. 4 is a right side elevational view thereof, the left side view being a mirror image thereof;

FIG. 5 is a back elevational view thereof; and,

FIG. 6 is a bottom plan view thereof.

The broken line showing is for environmental purposes only and forms no part of the claimed design.
